H. M. SHEER,
ANTIROOTER INSTRUMENT,
APPLICATION FILED APR. 3, 1915.

1,149,959.

Patented Aug. 10, 1915.

UNITED STATES PATENT OFFICE.

HENRY M. SHEER, OF QUINCY, ILLINOIS.

ANTIROOTER INSTRUMENT.

1,149,959.

Specification of Letters Patent. Patented Aug. 10, 1915.

Application filed April 3, 1915. Serial No. 18,866.

To all whom it may concern:

Be it known that I, HENRY M. SHEER, a citizen of the United States, residing at Quincy, in the county of Adams and State 5 of Illinois, have invented certain new and useful Improvements in Antirooter Instruments, of which the following is a specification.

My invention relates to an improvement 10 in anti-rooter instruments, the object being to provide an instrument for severing the cord on the bridge of a hog's nose, which will effectually prevent his rooting and preclude the possibility of the cord growing together and requiring a second operation.

In the accompanying drawings:—Figure 1 is a view in perspective; Fig. 2 is a side elevation with a portion broken away, the full lines showing the normal position of 20 the cutters or blades, and the dotted lines the position when the cutting operation is practically completed; Fig. 3 is a view looking toward the knives or cutters; Fig. 4 is a transverse vertical sectional view through 25 the instrument at the point where the knives or cutters are pivoted; and Fig. 5 is a fragmentary view showing a single pair of knives or cutters centrally mounted. Fig. 6 is a modification.

30 A, represents a sleeve or frame; and 1, is a rod fitted to slide therein. The frame A has the two finger-pieces 2, 2, beneath which the operator inserts his first two fingers, and the rod 1 has the crotch 3 to receive the 35 thumb where it joins the hand. The parts 2 and 3 are preferably set at an angle to each other, as shown in Fig. 3, to conform more nearly to the relative position of the parts of the hand, namely the base of the thumb 40 and two first fingers, to make it as easy as possible for the operator to manipulate the instrument.

A spring 4 fills the space between the frame or sleeve and the crotch, and holds 45 them apart, as shown in Figs. 1 and 2.

Knives or cutters 5, 5, and 6, 6, are pivotally mounted on the stud 7 carried by the end of the rod, washers 8, 8, being employed to hold the knives or cutters suitably spaced 50 and in position. The links 9, 9, pivotally connect the outer ends of the knives or cutters with the frame or sleeve A.

In the form shown in Fig. 5, a single set 55 of knives or cutters 10 and 11 is shown, the lower end of the rod 1 being divided or bi-

furcated as at 12 to receive them and the washers 13, 13 on the stud 14.

The shape of the knives or cutters is peculiar, as shown, namely they are in the general form of a compound curve, terminating in the sharp edges 15, 15, which ordinarily are protected by the adjacent knife, as shown in Fig. 2, and which do the cutting, they terminating in the sharp hook-like points 16, 16, which make the first incision 65 in the cord to be cut.

In applying the instrument, it is held with its parts in the normal position shown in full lines in Fig. 2, and placed with the points 16, 16, astride the cord to be severed. 70 This can be done without either afrighting or hurting the animal; and by a quick pressure or contraction between thumb and fingers, while thus holding, the spring 4 is compressed, the instrument naturally will 75 be forced firmly against the snout of the animal, while the cutting of the cord proceeds, which is done quickly and with a minimum of pain.

While it is preferred to make two cuts at 80 a time so that a section of the cord is cut out to prevent their growing together later, and for this reason the double set of blades as shown in Figs. 1, 2, 3 and 4 is preferred, still a single set might be employed, as shown in 85 Fig. 5, and two incisions be made.

The spring itself when compressed is adapted to serve as a stop to prevent further movement of the hook end of the knives or cutters, it being intended that they should 90 just a little more than meet each other when the spring is compressed.

The holes 17, 17, afford a convenient means of lubricating the moving parts.

More or less slight changes might be resorted to in the form and arrangement of the several parts described without departure from the spirit and scope of my invention, and hence I do not wish to be limited to the precise construction herein set forth, 100 as for instance in Fig. 6 is shown a construction in which the spring is dispensed with, and the sliding parts A' and 1' are provided with finger and thumb holes 2' and 3' to enable the operator to move the 105 parts positively in both directions without the aid of a spring.

I claim:

1. An anti-rooter instrument comprising two parts slidably connected together and 110

spring-actuated, one having handles and the other a crotch set at an angle to each other to receive the fingers and thumb, knives or cutters pivotally connected with one part, and links extending from the free ends of one moving part to the other moving part.

2. An anti-rooter instrument comprising two parts slidably connected together and spring-actuated, correspondingly shaped knives or cutters having hooked or pointed ends and sharpened adjacent thereto, said sharpened portion of each knife or cutter guarded normally by another knife or cutter, a spring normally holding the knives or cutters open, these knives or cutters pivoted to one of the sliding parts, and links extending from the free ends of the knives or cutters to the other sliding part.

Copies of this patent may be obtained for five cents each, by addressing the "Commissioner of Patents, Washington, D. C."

3. The combination of a frame or sleeve having finger-pieces thereon, a rod slidably fitted therein having a crotch on one end, and a compressible spring mounted on the rod and confined between the end of the sleeve or frame and the crotch, knives or cutters pivotally connected with one end of the rod, and links extending from the free ends of the knives or cutters to the frame or sleeve, whereby the knives or cutters are controlled by the relative positions of the sleeve and rod.

In testimony whereof I affix my signature, in the presence of two witnesses.

HENRY M. SHEER.

Witnesses:

ESTHER C. BRINKOETLER,

J. R. BAUMBERGER.
